UNITED STATES PATENT OFFICE.

CHARLES W. KIRSCH, OF STURGIS, MICHIGAN, ASSIGNOR TO KIRSCH MANUFACTURING CO., OF STURGIS, MICHIGAN, A CORPORATION OF MICHIGAN.

CURTAIN-FIXTURE.

1,281,024.

Specification of Letters Patent.

Patented Oct. 8, 1918.

Application filed November 24, 1917. Serial No. 203,764.

To all whom it may concern:

Be it known that I, CHARLES W. KIRSCH, citizen of the United States, residing at Sturgis, in the county of St. Joseph and State of Michigan, have invented certain new and useful Improvements in Curtain-Fixtures; and I do hereby declare the following to be a full, clear, and exact description of the invention, such as will enable others skilled in the art to which it appertains to make and use the same.

This invention has for its object to provide an improved curtain fixture particularly adapted for use in connection with French windows and doors, and generally in front of window and door openings which it is desired to maintain open at intervals for purposes of ventilation. It has for its particular object to provide a curtain fixture of the character defined which will permit the curtains to be swung back from their normal position in front of the opening, to opposite sides of the same against the wall at each side of the said opening so as to permit a complete and wide opening of the swinging window frames or doors without danger of tearing or otherwise injuring the curtains, and at the same time to dispose the latter out of the path of air currents carrying dust, smoke and the like, passing through the opening, thereby maintaining the curtains clean for a longer period than ordinarily.

A further object of the invention is to provide a curtain fixture of the character defined including curtain rods which are firmly maintained in their normal position by means resisting swinging movement of the same, but which will permit the same to be readily swung by engaging the curtains below the said rods and merely lightly pulling on the same to overcome such resistance. The invention also comprehends means for positively locking the curtain rods in their normal position by manually operable means.

Other objects of the invention will be readily understood from the following description.

The invention consists in the features of construction and combinations of parts hereinafter fully described and particularly claimed.

In the accompanying drawings illustrating the invention:

Figure 1 is a top plan view of a curtain fixture embodying my invention.

Fig. 2 is a front elevation of the same.

Fig. 3 is a fragmentary detail vertical section on an enlarged scale on the line 3—3 of Fig. 1.

Fig. 4 is an end elevation of the same.

Fig. 5 is a view similar to Fig. 1 showing a modified form of construction.

Fig. 6 is a front elevation of the same.

Fig. 7 is a detail vertical section on the line 7—7 of Fig. 5.

Fig. 8 is an end elevation of the structure shown in Figs. 5 and 6.

The curtain fixture comprises a pair of 70 brackets and a pair of rods associated therewith. Each of the brackets comprises a plate 1 adapted to be secured to a window casing, door frame or the like, and which is provided with a pair of parallel horizontal flanges 2 and 3 which are provided at their outer ends with openings to receive the pivot pin 4.

Each of the rods secured to the brackets comprises a long arm 5 and a short arm 6, 80 the latter extending at right angles to the former and to the plane of the window casing or door frame to which the bracket is secured. The said rod is preferably of the flat type, C-shaped in cross section, and consists of a plurality of telescopically interfitting members of well-known type illustrated and described in Letters Patent No. 1,210,947, dated Jan. 2, 1917; No. 1,187,914 dated June 20, 1916; No. 1,240,582, dated Sept. 18, 1917 and others. The pivot pin 4 passes through openings in the flanges of the arm 6 of the rod between the ends of the latter, and substantially midway between said ends, or midway between the 95 horizontal plane of the portion 5 of the rod and the opposed surface to which the plates 1 are secured. The rod is thus enabled to swing through an arc of substantially one hundred and eighty degrees so that French windows or hinged doors before which the curtains are suspended from the rods may be opened wide or through an arc of substantially one hundred and eighty degrees without coming into contact with and tearing or otherwise injuring said curtains,

100
105

Each of the plates 1 is provided along one edge with a flange 7 against which the inner end of the arm 6 is adapted to abut when the rod is in its normal position so that the curtains are suspended in front of and parallel with the plane of the window casing or door frame. Mounted on the plate 1 are means coacting with the said stop flange 7 for firmly holding the rod in its former position. These means may consist, as shown in Fig. 1, of the lever 8 pivotally secured between its ends to the plate 1 which is provided at one end with a substantially V-shaped projection 9, one edge of which normally engages the upper flange of the arm 6, and serves to press said arm 6 against said flange 7. A spring 10 mounted on the flange 3 of the bracket bears at its free end upon the upper edge of said lever 8 contiguous to or above the said projection 9 thereof, and exerts a yielding pressure thereon which is transmitted to the arm 6, as will be obvious, to force the same into engagement with the flange 7. The other end of the lever has a cord, or the like, attached thereto, which may be pulled downwardly by the operator to raise the projection 9 out of the path of the arm 6 to enable the rod to be freely swung through an arc of approximately one hundred eighty degrees. The edge of said V-shaped projection 9 which is normally engaged with the arm 6 is only slightly inclined so as to exert a wedging force on the arm 6 and will not permit said arm to force said projection out of its path by attempting to turn said rod without pulling said cord 11, but the other edge of said projection 8 is disposed at such an incline that upon returning the rod to its normal position the said lever 8 will be turned on its pivot against the action of the spring 10 without necessitating manual operation of the lever 8 by means of said cord 11.

In place of the manually operable lever 8 a yielding latching means may be provided such as shown in Figs. 5 to 8 inclusive, which consists of a flat spring 12 extending parallel with the plate 1, and which is secured at one end upon the flange 3. The other end of said flat spring terminates in a V-shaped projection 13, one face of which normally bears upon the upper flange of the arm 6 of the rod to firmly but yieldingly hold the latter in engagement with the stop flange 7. The inclination of both arms of the V-shaped end portion of said spring 12 is such that a relatively slight force exerted on the rod to turn the same on its pivot away from the flange 7 will overcome the resistance offered by the spring 12, and move the projection 13 out of the path of the arm 6 thus permitting the rod to be freely swung to its open position. The return of the rod to its normal position will

cause the other inclined surface of the projection or end portion 13 of the spring 12 to be sprung out of the path of the upper edge of the arm 6 and, as the latter moves into engagement with the flange 7, said spring 70 will move back to the position shown in Fig. 8, thereby again firmly but yieldingly holding the rod in its normal position.

It will be observed that by reason of the location of the pivot pin 4 between the ends of the arms 6 of the rod that the hems of the curtains or drapes 16 suspended from the said rods will not normally be enabled to cover that end portion of said rod which lies between the pivot pin 4 and the plate 80 1. Accordingly, I provide on the arm 6 a depending U-shaped wire or rod 15 which is secured thereto at a point between the pivot pin 4 and the junction of the arm 6 with the arm 5 of the rod. The middle 85 portion of the wire or rod 15 is disposed below the flange 2 parallel with the latter and extends rearwardly to a point contiguous to the end of said arm 6. The curtain must be cut and hemmed so that a portion 17 is 90 provided which is slipped over the said U-shaped arm 15 to suspend a part of the curtain from below said arm 6 and extending substantially to the end of said arm 6.

While I have shown the preferred embodiment of the invention in the accompanying drawings, it will be understood, of course, that said construction may be changed and varied in details without departing from the invention as defined in the appended claims.

I claim as my invention:

1. A curtain fixture including brackets adapted to be mounted on a window casing or the like, curtain rods each pivoted contiguous to one end to one of said brackets for swinging in a horizontal plane, and an extension member on the pivoted end portion of each rod projecting underneath the bracket for permitting a curtain to be 110 draped throughout the entire length of the rod and out of engaging relation to the bracket.

2. A curtain fixture including brackets adapted to be mounted on a window casing 115 or the like, curtain rods each having a long and a short arm extending angularly relatively to each other and each having its short arm pivotally secured to one of said brackets for swinging in a horizontal plane, 120 and an extension member mounted on the short arm of each rod and projecting underneath the bracket and through the pivotal axis of the rod for permitting a curtain to be draped throughout the entire length 125 of the rod and out of engaging relation to the bracket.

3. A curtain rod comprising a bracket, a curtain-supporting member pivotally mounted thereon, a stop for limiting the piv- 130

otal movement of said member in one direction, and latching means for holding said member normally engaged with said stop.

4. A curtain rod comprising a bracket, a curtain-supporting member having two relatively transversely disposed arms, pivotal connection between one of said arms between the ends thereof and said bracket for permitting said member to swing through an arc of substantially one hundred eighty degrees, and a stop on said bracket for limiting the movement of said member in one direction.

5. A curtain rod comprising a bracket, a curtain-supporting member having two relatively transversely disposed arms, pivotal connection between one of said arms between the ends thereof and said bracket for permitting said member to swing through an

arc of substantially one hundred eighty degrees, a stop on said bracket for limiting the movement of said member in one direction, and latching means for normally maintaining said member engaged with said stop.

6. A curtain rod comprising a bracket, a curtain-supporting member having two relatively transversely disposed arms, pivotal connection between one of said arms between the ends thereof and said bracket for permitting said member to swing through an arc of substantially one hundred eighty degrees, a stop on said bracket for limiting the movement of said member in one direction, and means associated with said member and said bracket for yieldingly holding said parts firmly in relative position when said member attains its normal position.

CHARLES W. KIRSCH.
